UNITED STATES PATENT OFFICE.

WILLIAM E. BROWN, OF PATRICIA, TEXAS.

SPINNING TOP.

Application filed October 8, 1928. Serial No. 311,206.

This invention relates to spinning tops, one of the objects being to provide a toy of this character which can be operated without the usual cord ordinarily wrapped about the top and subsequently pulled therefrom.

A further object is to provide a top which can be caused to spin on a supporting surface or can be used as a gyroscope suspended from a cord.

10 With the foregoing and other objects in view which will appear as the description proceeds the invention resides in the combination and arrangement of parts and in the details of construction hereinafter described and claimed it being understood that changes in the precise embodiment of the invention herein disclosed may be made within the scope of what is claimed without departing from the spirit of the invention.

20 In the accompanying drawings the preferred forms of the invention have been shown.

In said drawings,

Figure 1 is an elevation of a top and one form of operating means provided therefor.

Figure 2 is an elevation of the top with another form of operating means.

Figure 3 is a top plan view of the top.

30 Figure 4 is a section through the top showing the same suspended by a cord for spinning like a gyroscope.

Referring to the figures by characters of reference, 1 designates the body of the top which can be formed of sheet metal or any other suitable material and has a central stem 2 extending therethrough, one end of the stem being pointed and extending a short distance from the body as shown at 3 while the other end of the stem is extended a greater distance from the body and is provided with an annular groove 4 near its free end.

Formed in the body at the top and bottom thereof are openings 5 and 6 which are out of alignment, the stem being extended between them.

The operating means consists of a single length of wire bent to form an elongated coil having a handle at one end, the coil being indicated at 7 and the handle at 8.

If it is desired to spin the top on a supporting surface the spiral 7 is inserted into the opening 5 and around the stem 2 and is

screwed through the body 1, emerging at the opening 6. By holding the body 1 the spiral or coil 7 will gravitate therethrough until the handle portion 8 is brought against the body 1. A push wire 9 is then inserted into the coil so as to bear against the end of stem 2 and by thrusting the rod longitudinally the top will be pushed off of the coil.

As the top is pushed off of the coil it will be rotated thereby, it being possible, by giving a rapid thrust against the stem, to cause the body to rotate at a high speed. The pointed end 3 of the stem will drop on to a supporting surface and the top will then spin like an ordinary top.

Instead of operating the top as described one end of a cord 10 can be fastened loosely within the groove 4 and the body 1 can be reversed so that the coil will first enter the opening 6 and then emerge through the opening 5. By holding the body 1 the coil 7 can be caused to gravitate therethrough as heretofore explained and during this action a portion of the cord will be received by the coil as shown in Figure 2. Thereafter, by pulling on the cord 10 the body can be pulled off of the coil during which time the coil will rotate it at a high speed. Thus after the body leaves the coil it will be suspended from the cord and will spin at any desired angle relative thereto. See Figure 4.

What is claimed is:

1. The combination with the body of a spinning top having a stem, of actuating means including a coiled wire threaded through the body and around the stem, and means within the coil for shifting the body longitudinally of the coil thereby to spin the body and remove it from the coil.

2. The combination with the body of a spinning top having a stem, of actuating means including a coiled wire threaded through the body and around the stem, and means within the coil and engaging the stem for shifting the body longitudinally of the coil thereby to spin the body and remove it from the coil.

In testimony that I claim the foregoing as my own, I have hereto affixed my signature.

WILLIAM E. BROWN.
